UNITED STATES PATENT OFFICE.

JOHN STEVENSON, OF EDINBURGH, SCOTLAND.

CHANGEABLE PICTURE.

SPECIFICATION forming part of Letters Patent No. 736,035, dated August 11, 1903.

Original application filed January 15, 1901; Serial No. 43,402. Divided and this application filed February 24, 1903. Serial No. 144,806. (No model.)

To all whom it may concern:

Be it known that I, JOHN STEVENSON, a subject of the King of Great Britain and Ireland, and a resident of 4 Albert Terrace, Trinity, 5 Edinburgh, county of Mid-Lothian, Scotland, have invented a certain new and useful Changeable Picture, (which I have divided out from Serial No. 43,402, filed January 15, 1901, and for which I have made application 10 for Letters Patent in Great Britain, No. 17,783, dated October 6, 1900,) of which the following is a specification.

My invention relates to an improved method of representation of designs or characters 15 upon paper, cloth, or other material and the picture produced thereby; and the object of the invention is to enable a gradually-changing effect in the designs to be obtained under the action of light or internal chemical action 20 or chemical action resulting from exposure to the atmosphere.

The invention consists of printing a representation in a permanent color then applying over said representation, so as to conceal or 25 cover the same, a color of different hue which is non-permanent and disappears when exposed to light, and then exposing the representation to the action of light, whereby the non-permanent color disappears and leaves 30 the representation in a permanent color.

It also consists of a changeable picture produced by practicing the said process.

In carrying the invention into effect I employ for making a design pigments of different color, one or more of which may be permanent and the remainder non-permanent. 35 In making a design from permanent and non-permanent colors one color is applied first to the paper or other material, and the remaining colors are superimposed upon it. On exposing the design to the light the non-permanent colors disappear and leave the permanent color or colors to indicate the design.

In order that my invention may be clearly 45 understood, I shall now particularly describe it with reference to the accompanying drawings, in which—

Figure 1 represents the appearance of one form of prepared print in accordance with my 50 invention. Fig. 2 represents the same print

after it has been exposed to the action of light for some time; and Fig. 3 represents the fully-exposed print, showing the developed picture. Fig. 4 represents a design in which letters or characters are printed in accordance with my invention. Fig. 5 represents the result of exposing the design to the action of light.

Referring now to Figs. 1 to 3, in carrying out my invention according to one modification I print in one or more colors, according to any of the well-known processes of printing a picture—for example, such as is seen in Fig. 3—and over the whole picture I apply a dark non-permanent color-pigment, so as to 60 completely obliterate the picture, the result being similar to that represented in Fig. 1. In addition to the fugitive dark pigment employed for rendering the whole picture invisible some of the colors of the different parts 65 of the design may be overlaid with non-permanent color, which is not so fugitive as the dark obliterating color. For example, in the design shown in Fig. 3 the leaves *a* may be printed in permanent green, while the rose *b* may be printed in permanent yellow covered over by some color—for example, an impermanent white—which is relatively less fugitive than the dark obliterating color. The result after partial exposure of the print seen in 70 Fig. 1 is as illustrated in Fig. 2, where the dark obliterating color has practically completely disappeared, showing the picture with its colors partially developed, the leaves *a* then appearing in green color and the rose *b* with 75 its outlines incompletely defined. Upon further exposure the picture appears, as illustrated in Fig. 3, in its natural permanent colors, showing a yellow rose with green leaves. In applying my invention for the purpose 80 of producing changeable representations in printed letters or characters I first print in permanent pigment or ink a combination of letters which forms an intelligible word or words—for example, such as is seen in Fig. 5. 85 I then add to the letters by printing in non-permanent colors any arrangement of markings which will render the words unintelligible, as illustrated in Fig. 4, where the non-permanent parts are indicated by the double 90 95 100

lines *c*. Upon exposure to light of the design shown in Fig. 4 the parts marked *c* disappear, producing the original intelligible words.

5 It will be obvious that according to my invention many varied effects pleasing to the eye may be produced.

Having thus described my invention, what I claim as new, and desire to secure by Letters

10 Patent, is—

1. The process of producing pictures consisting of printing a representation in a permanent color, then applying over said representation, so as to conceal or cover the same, 15 a color of different hue, which is non-permanent and disappears when exposed to light, and then exposing the representation to the action of the light, whereby the non-perma-

nent color disappears and leaves the representation in a permanent color.

2. As a new article of manufacture, a changeable picture consisting of a representation printed in at least two colors one of which is permanent and forms the actual representation, and another is non-permanent and disappears when exposed to light, is of a different hue from the permanent color, and is applied all over said permanent color so as to temporarily conceal or cover the same.

In witness whereof I have hereunto set my 30 hand in presence of two witnesses.

JOHN STEVENSON.
